CANOE

Brent G. Biehl, 19796 Damman St., Harper Woods, Mich.

Filed June 10, 1965, Ser. No. 85,667

Term of patent 14 years

(Cl. D71—1)

FIG. 2

FIG. 3

FIG. 4

FIG. 5

FIG. 6

FIG. 1 is a perspective view, taken from the left side, of a canoe, showing my new design, the right side being identical in appearance.

FIG. 2 is a perspective front view thereof.

FIG. 3 is a left side elevational view of the front portion thereof.

FIG. 4 is a perspective view taken from the rear right side thereof.

FIG. 5 is a perspective view taken from the rear left side, showing the bottom thereof.

FIG. 6 is a cross-sectional view thereof, taken in the direction of lines 6—6 on FIG. 1.

The characterizing features of my design reside in: the curvature of the bow and/or the stern which becomes nearly horizontal at the upper edge and terminates in a downwardly curving enclosing deck, and said up-

per edge being approximately twice the height of the hull portion intermediate the bow and stern.

I claim:

The ornamental design for a canoe, as shown and described.
